SERVICE VALVE FOR PORTABLE CONTAINERS

Cecil W. Ashley, Fort Worth, Tex.

Application June 20, 1941, Serial No. 398,898

3 Claims. (Cl. 222—501)

This invention relates to a service valve assembly for liquid containers or drums and it has particular reference to the type of gate valve known as an oil or molasses gate for dispensing such commodities from portable containers commonly provided only with an integral fitting into which a conventional plug is threaded to be removed to receive a detachable valve, and its principal object resides in the provision of a service valve adapted to be installed in the container to become a permanent part thereof and designed to be retracted into the container and extended therefrom to provide a suitable discharge spout for conducting the contents from the said container into another vessel.

Another object of the invention resides in the provision of a service or gate valve capable of being installed in the conventional container having standard fittings therein, yet adapted to be retracted or urged back into the container and locked in such position for transportation to avoid the necessity for removing the said valve for such purposes, thus maintaining the device in condition, at all times, for ready use but without the awkward and unsightly extension which would be occasioned by the use of a conventional rigid valve incapable of retraction into the container.

Yet another object of the invention is manifest in the provision of the novel closure arrangement for the inner end of the valve, interiorly of the container, which is designed to afford the maximum surface against which the liquid contents of the container may be applied to close the valve and retain the same in closed position, aided by a spring, until the closure is manipulated by a suitable plunger arrangement exteriorly of the container.

An important object of the invention resides in the provision of a compact trap adapted to close the outer end of the valve and at once lock the same in its retracted position in the container, thus minimizing the projections thereon and consequently the hazards experienced in handling whereby conventional valve arrangements may be injured or knocked off; if allowed to remain in the container during shipment or transportation, the closure trap occupying no more space than ordinarily required for the conventional plug usually applied to the opening in which the conventional valve is installed.

Broadly, the invention seeks to comprehend the provision of a novel valve assembly which is economical in construction and capable of use

in connection with the dispensing of all types of liquid products to expedite the dispensing operation and minimize leakage, as well as to afford a great saving in time commonly required to remove and install conventional type valves and to include in such assembly a dependable locking means whereby access may be gained to the contents of the said container by only authorized persons.

10 While the foregoing objects are paramount, other and lesser objects will become manifest as the description proceeds taken in connection with the appended drawing wherein:

Figure 1 is a longitudinal cross sectional illustration of the valve installed in a conventional fitting and showing the closure assembly in a closed position but illustrating the same open in dotted lines.

Figure 2 is a view taken on lines 2—2 of Figure 1 and showing the invention in lateral cross section.

Figure 3 illustrates a modified form of the invention in longitudinal section in which an especially designed fitting is employed.

25 Figure 4 is a front end view of the invention illustrating slotted apertures in the cap flange and the set screw locking device for the cap.

Figure 5 illustrates another modification of the invention showing the sleeve rigidly secured 30 to the fitting to form a fixed discharge spout, and

Figure 6 is a perspective illustration of the preferred form of trap for closing the outer end of the valve.

35 Accordingly, therefore, the invention comprises primarily a sleeve 1 which, in its preferred form, is slidably arranged within a fitting 2 which may be exteriorly threaded at a and adapted to be threadedly secured within an interiorly flanged fitting 3 of the conventional type employed in steel containers or drums, the wall 4 of such a container being fragmentarily shown in Figure 1.

Both ends b and c of the sleeve 1 are preferably upset slightly, as illustrated, in the case of the outer end b to prevent the tube 1 from extending into the container beyond the outer face d of the fitting 2 and in the case of the inner end c to afford both a suitable stop to limit the external extension of the sleeve 1 and provide a suitable seat for the substantially conical diaphragm closure 5 arranged within the inner end of the sleeve 1.

The closure member 5 is connected to the inner end of a plunger 6 through the medium of

nuts 7 and washers 8 of some pliable material having the consistency of rubber, or the like, but not subject to the deteriorating effect of oils and other fluids containing acids and similar corrosive properties. This arrangement affords a flexible connection between the closure 5 and the plunger 6 whereby, due to the substantial conical shape of the member 5, the latter can be properly seated against the upturned end c of the sleeve 1.

The opposite end of the plunger 6 is rigidly connected with a lever 9, which is substantially L-shaped, having a vertical and horizontal leg 10 and 11. The lever and plunger assembly are operatively mounted in a bracket 12 rigidly secured to the inner top of the sleeve 1 which is provided with downwardly depending legs 13 and 14, the former having an opening 15 in its lowermost end slidably accommodating the horizontal leg 11 of the lever 9 while the vertical leg 13 of the member 12 is likewise provided with an opening 16 slidably accommodating the plunger 6, each of the members 13 and 14 functioning also as suitable guides for the plunger 6 and the lever 9.

A plurality of notches 17 forming one or more angular teeth 18 are provided in the upper side of the leg 11 of the lever 9 for the purpose of temporarily locking the latter within the opening 15 of the member 13 to retain the closure 5 away from the seat c and permit the flow of liquid through the sleeve 1 from the container 4. A plurality of the notches 17 is provided in order to afford adjustability or the variable positioning of the closure 5 with respect to the inner end c of the sleeve 1, as illustrated in dotted lines in Figure 1.

As previously stated, the sleeve 1, in the preferred form of the invention, is slidable with respect to the fitting 2 and for this reason it is desirable to afford a packing ring 19 which is inserted in an annular recess e in the outer face d of the fitting 2, as illustrated in Figures 1 and 2. This arrangement insures a close fit exteriorly of the member 1 within the fitting 2 to prevent leakage and also provides for a proper seal around the rear surface of the outer end b of the sleeve 1 when the valve is retracted into the container and locked in closed position.

The outer closure or cap 20 is formed with a flange 21 at its base having a plurality of spaced apertures 22 each having lateral communicating slots 23 adapted to engage the hoods of a plurality of studs 24 spaced about the outer face d of the fitting 2 by which the cap 20 can be rigidly secured to the member 2 retaining the sleeve 1 in its retracted position within the drum 4.

It is obvious that by reason of the shape of the member 5 the pressure of the fluids contained within the drum 4 will bear against the inner face of the member 5 and not only retain the same in its closed position against the inner end c of the sleeve 1 but such pressures will also serve to urge the sleeve outwardly to the limit of its extension, as illustrated in Figure 1, to provide a dispensing spout. It is essential, therefore, that some means be provided, such as the elements 21, 22, 23 and 24, to secure the cap 20 to the member 2 in order to retain the sleeve 1 in its retracted position within the container 4 against the pressure of the liquid therein. A suitable packing ring 25 affords the proper seal around the cap 20 against the outer end b of the sleeve 1 or the face d of the member 2 to prevent leakage. Similarly a sealing compound forming a

ring f may be afforded around the inner end c of the sleeve 1, as shown in Figure 1.

While the liquid pressures within the container 4 are deemed sufficient to retain the closure 5 against its seat on the inner end c of the sleeve 1, it is considered desirable to provide a spring 26 on the plunger 6 which aids in drawing the closure 5 against its seat. The spring 26 bears in each direction against the lever 9 on its outer end and the lowermost end of the vertical leg 14 of the bracket 12 and is always under a slight tension calculated to urge the member 5 against its seat in the manner heretofore described.

It will be noted that the modification illustrated in Figure 3 is similar in all respects to the form of the invention shown in Figure 1 except that the conventional fitting 3, commonly installed in the wall of the container 4, is supplemented by an especially designed fitting 21 having smooth inner and outer surfaces instead of the threaded outer surface, as illustrated in Figure 1, which may be welded into the opening provided in the wall of the container 4, or it may be otherwise secured therein, and adapted to receive the sleeve 1 without the use of the internal fitting 2. In other words, in the modification illustrated in Figure 3 the members 2 and 3 employed in the structure shown in Figure 1 can be combined, thus eliminating one of the parts.

The closure element 5, the plunger 6 and the lever assembly 9, 10 and 11 may be also operatively supported within the sleeve 1 by an arrangement similar to the brackets 12, illustrated in Figure 1, whereby the variable adjustments of the closure 5 with respect to its seat may be accomplished. The cap 20 may also be provided with an extending cylindrical portion 28 of a slightly lesser diameter than the internal diameter of the sleeve 1 so that the member 28 can be inserted into the latter, as illustrated in Figures 1 and 3, and slotted at 29 to provide a bayonet joint for locking the cap upon the sleeve 1. This arrangement is also provided in the structure illustrated in Figure 5. The slot 29 is adapted to receive an internally projecting lug 30 within the sleeve 1 which engages the slot 29 to retain the cap 20 rigidly thereon.

In some instances a non-retractable rigid valve assembly is desirable and the modification illustrated in Figure 5 is provided for this purpose. The sleeve 1 is secured, preferably by welding g, or other suitable means, to a fitting similar to the element 2 in Figure 1. The assembly can then be threaded into the conventional fitting 3, commonly installed in the wall of a container 4, and allowed to project therefrom in the usual manner. In transporting the container the assembly may be removed from the fitting 3 and the conventional plug inserted in the opening.

A locking arrangement comprising a boss 31 integral with the sleeve 1 interiorly threaded to receive a set screw 32, preferably of the Allen type, may be arranged on the valve, in the manner illustrated in Figure 5, to lock the cap 20 in position on the sleeve 1 and prevent the same from removal by unauthorized persons. It is desirable to provide the set screw 32 with a recess in its top capable of accommodating a special key only, such as that ordinarily employed with the Allen type set screw, and such locking arrangement may also insure against the accidental opening of the valve, or removal of the cap 20, through vibration, or the like. A

similar locking arrangement is provided for the cap 20, as illustrated in Figure 4.

Manifestly, the invention is capable of considerable changes and modifications by persons skilled in the art and such changes and modifications which may be resorted to from time to time which are considered as coming within the spirit and intent of the invention may also be considered as falling within the scope of the appended claims.

What is claimed is:

1. In a liquid service valve for portable containers having a fitting secured in the wall of the container and a sleeve slidably arranged through the said fitting, a conical diaphragm member having its inner face amenable to the pressure of the liquid within the said container to close the inner end of the said sleeve, a plunger operatively arranged in the said sleeve and connected to the said diaphragm member and a lever on said plunger providing means for manually operating the said diaphragm to open and close the same.
2. In a liquid service valve for portable containers having a fitting secured in the wall of the said container and a sliding extensible and

retractible sleeve arranged in the said fitting, a conical closure adapted to seat against the inner end of the said sleeve designed to be acted upon by pressures within the said container, a plunger operatively arranged in the said sleeve and flexibly connected to the said closure for manually opening and closing the same and means comprising a lever having notches therein and associated with the said plunger adapting the said closure to be variably positioned with respect to its seat.

3. In a valve assembly for containers having a fitting secured in the wall thereof and an extensible and retractile sleeve arranged in the said fitting, means comprising a substantially conical member interiorly of the said container providing a pressure actuated closure for the inner end of the said sleeve, a tensioned manually operated plunger flexibly connected with the said closure having a lever connected thereto formed with retaining notches thereon providing for the variable positioning of the said closure with respect to its seat and a frame structure rigidly secured in the said sleeve supporting the said lever and plunger.
